UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,549, dated December 31, 1889.

Application filed December 7, 1889. Serial No. 332,970. Term of patent 3½ years.

To all whom it may concern:

Be it known that I, WILLIAM K. BENEDICT, of the city and county of New York, in the State of New York, have invented and produced a new and original Design for the Exterior of a Residence, of which the following is a specification, reference being had to the accompanying drawings, forming a part thereof.

10 Figure 1 represents a perspective view of a residence showing my design. Fig. 2 represents a horizontal section or plan of the first story. Fig. 3 represents a horizontal section or plan of the second story.

15 Similar letters of reference designate corresponding parts in all the figures.

A residence embodying my design is generally rectangular in the ground plan, and comprises a substantially square portion A, 20 an extension B projecting rearwardly from the portion A. The whole is surmounted by gable roofs, which in the case of the portion A extend downwardly to about the top of the second story. The house is provided with 25 bays, porches, and dormer-windows, which I will describe more in detail.

The front of the first story C is illustrated as being provided with a porch D, having a shed-roof b. At one corner of the house there 30 is illustrated a rectangularly-shaped portion E of the porch, surmounted with a gable roof. At one side of the porch E and extending along the side of the house is a porch a, surmounted by a shed-roof a'. To the rear of

the portion a of the porch the dwelling has a 35 substantially flat and vertical exterior c. To the rear of the portion c is shown a jog d, and beyond the jog d one side of the extension B. This extension comprises a second-story portion e, having a gable roof e'. The first-story 40 portion is surmounted by a hipped roof e'. At one side of the extension B is a porch F.

The second story illustrates upon its front a bay f, of rectangular form. Between the front of the second story and the side thereof 45 is an angle f'. In said angle and above the portion a of the porch is a balcony f''. The side of the second story is substantially vertical.

The third-story front is beneath a gable 50 roof G. The bay f is surmounted by a balcony g. Above the balcony g the front has a sunken or inset window g', above which is an overhanging g'', supported by consoles g''. Upon the gable roof G and facing toward the 55 side of the house is a dormer-window H, surmounted by a hipped roof. At the side of the house, in the third story, is an overhanging I, surmounting a sunken or inset window I''. Beneath the overhanging I are consoles i. 60

What I claim is—

A design for the exterior of a residence, substantially as herein shown and described.

WILLIAM K. BENEDICT.
